(57) **CLAIM**

The ornamental design for a glass solar panel, as shown and described.

DESCRIPTION

FIG. 1 is a front view of a glass solar panel according to the claimed design;

FIG. 2 is a perspective view thereof;

FIG. 3 is a front view of another embodiment of a glass solar panel according to the claimed design;

FIG. 4 is a perspective view thereof;

FIG. 5 is a front view of another embodiment of a glass solar panel according to the claimed design;

FIG. 6 is a perspective view thereof;

FIG. 7 is a front view of another embodiment of a glass solar panel according to the claimed design;

FIG. 8 is a perspective view thereof;

FIG. 9 is a front view of another embodiment of a glass solar panel according to the claimed design;

FIG. 10 is a perspective view thereof;

FIG. 11 is a front view of another embodiment of a glass solar panel according to the claimed design; and,

FIG. 12 is a perspective view thereof.

The glass solar panel is shown with symbolic breaks, formed by broken lines. The appearance of any portion of the article between the break lines forms no part of the claimed design. The broken lines shown in the drawings represent portions of the glass solar panel that form no part of the claimed design. Moreover, the claimed design is not limited to any particular size and may be scaled larger or smaller than depicted.

FIGS. 1-6 have been lined to indicate a transparent material.

1 Claim, 12 Drawing Sheets
